UNITED STATES PATENT OFFICE

CLYDE W. KELLY, OF DETROIT, MICHIGAN, ASSIGNOR TO DETROIT STEEL PRODUCTS COMPANY, OF DETROIT, MICHIGAN, A CORPORATION OF MICHIGAN

DOOR BUMPER

Application filed April 15, 1929. Serial No. 355,400.

The invention relates to door bumpers and has for one of its objects the construction of a sectional door bumper which may be readily clamped to an anchoring member and which has provision for receiving a cushion for engaging a door. Another object is to so arrange the bumper that it may be readily secured to a like bumper for another door and thereby held more firmly in place. With these as well as other objects in view, the invention resides in the novel features of construction and combinations and arrangements of parts as more fully hereinafter set forth.

In the drawings:—

Figure 1 is a side elevation of a door bumper shown in operative relation to a door;

Figure 2 is a plan view showing a plurality of door bumpers;

Figure 3 is an enlarged rear end view of a door bumper;

Figure 4 is an enlarged side elevation thereof;

Figure 5 is an enlarged cross section on the line 5—5 of Figure 1;

Figure 6 is a view similar to Figure 3, showing only a portion of the door bumper applied to a different anchoring member.

The door bumper embodying my invention is shown in the present instance for use with a sliding door 1 of an airplane hangar, which door is mounted upon wheels or rollers 2 movable along the head 3 of the I-beam rail 4. The airplane hangar has a plurality of these doors, each of which is movable along a track 35 having a portion extending parallel and adjacent to portions of the other tracks and there is a bumper for each door secured to and extending longitudinally of each of these track portions.

The door bumper is formed of the complementary cooperating sections 5, each section having a body formed with a side wall 6 and front and rear end walls 7 and 8, respectively. The side wall 6 is formed at its lower end with the channel-shaped projection 9 and at its upper end with the arcuate portion 10. For reinforcing each section there is the web 11 which extends transversely from the inner edge of the rear wall and above the arcuate portion 10. There are also the reinforcing

webs 12 which extend transversely of the side wall 6 near its lower end and in registration with and in continuation of the lower ends of the front and rear side walls. Each reinforcing web 11 terminates at a point adjacent to but spaced from the projection 9 to form a recess 13 for receiving the head 3 of the rail 4. Each projection 9 is adapted to engage the rail between the head 3 and the base 14 of the rail. The projections 9 of the cooperating sections, as well as the recesses 13 and the arcuate portions 10, are located to be opposite each other when these sections are clamped together and upon the rail, the arcuate portions with the upper portions of the rear wall 8 cooperating to form a cavity or cup to receive the cushion 15 for engaging the door, this cushion being preferably formed of rubber. To clamp the sections together and upon the rail which forms the anchoring member of the door bumper, I provide the bolts 16 which extend transversely through the side walls 6 near their lower ends and above the rail 4 and the nuts 17 threaded upon these bolts. I also provide the bolt 18 extending transversely through the reinforcing web 11 above the arcuate portions 10 and the nut 19 threaded upon this bolt for clamping the upper ends of the sections together and for clamping the cushion 15 in place.

For limiting the movement of the sections toward each other and at the same time reinforcing these sections, I have provided upon each section the transverse inwardly extending rib 20 which connects into the front and rear walls and is integral therewith as well as with the side wall.

The sections of the door bumper, as above described, are preferably malleable or steel castings which are of simple construction and yet strongly reinforced so that when assembled they have sufficient strength and stability to take the force exerted by a door without breaking. In this connection, the front walls 7 extend vertically and the rear walls 8 are inclined upwardly and inwardly relative to the front walls to form braces.

The side walls 6 of each section are preferably provided with the transverse apertures 21 located below the ribs 20 and when a num-

ber of adjacent parallel door bumpers are used, as shown in Figure 2 particularly, these door bumpers may be connected to each other by means of the rod 22 and the nuts 23 at opposite ends of the rod and spaced by means of the sleeves 24 located between the side walls of adjacent door bumpers, this arrangement providing for increasing the stability of each door bumper.

10 In the modification shown in Figure 6, the door bumper is secured to a different I-beam rail 25 and instead of the sides of the projections engaging the head and base of the I-beam rail, the faces 26 of the projections 15 engage the web of the I-beam rail.

What I claim as my invention is:

1. A door bumper having cooperating sections, each with spaced anchoring and cushion receiving portions, and means for clamping said sections together and upon an anchoring member.

2. A door bumper having cooperating sections with opposite parts for engaging between the head and base of an anchoring member on opposite sides thereof, and cavity forming portions for receiving a cushion and means for clamping said sections together and to the anchoring member.

3. A door bumper having cooperating sections, each section having a body formed with a projection for engaging between the head and base of an anchoring member at one side thereof and with an arcuate portion, and a reinforcing web extending from said arcuate portion and merging into said body adjacent to but spaced from said projection to form therewith a recess for receiving one side of the head of the anchoring member, said projections and arcuate portions being respectively opposite each other, and means for clamping said sections together and to the anchoring member.

4. The combination with an I-beam anchoring member, of a door bumper secured thereto having cooperating sections, each section having a body with a side wall formed with a projection for engaging between the head and base of said I-beam anchoring member at one side thereof and with an arcuate portion and a back wall, and a reinforcing web extending transversely from said back wall, said projections and arcuate portions being respectively opposite each other, a cushion between said arcuate portions, and means adjacent to said projections and arcuate portions for clamping said sections together and to said I-beam anchoring member.

5. The combination with spaced anchoring members, of door bumpers secured to said anchoring members, each door bumper having cooperating sections with anchoring portions at one end and cushion receiving portions at the other end and means for clamping said sections together, and means for se-

curing said door bumpers relative to each other including a rod extending through the sections thereof, and spacers between the adjacent sections of adjacent bumpers.

6. A door bumper having cooperating sections, each with spaced anchoring and cushion receiving portions and a transversely extending reinforcing web adjacent said anchoring portion, and means for clamping said sections together, and upon an anchoring member.

7. A door bumper having cooperating sections, each with spaced anchoring and cushion receiving portions and a pair of spaced transversely extending reinforcing webs adjacent said anchoring portion, and means for clamping said sections together and upon an anchoring member.

8. A door bumper having cooperating sections, each with spaced anchoring and cushion receiving portions, of means for clamping said sections together upon an anchoring member, and cooperating means upon said sections for limiting movement of the sections toward each other.

9. A door bumper having cooperating sections, each section having a body provided with spaced anchoring and cushion receiving portions, each of said sections having a vertical front edge portion and a rear edge inclined upwardly and inwardly toward the front edge, and means for clamping said sections together upon an anchoring member.

10. A door bumper having cooperating sections, each having a body provided with spaced anchoring and cushion receiving portions and having a vertical front wall and a rear wall inclined upwardly and inwardly relative to said front wall, and means for clamping said sections together upon an anchoring member.

In testimony whereof I affix my signature.

CLYDE W. KELLY.
